DESCRIPTION

U.S. PATENT DOCUMENTS

D578,678 S * 10/2008 Huang D26/28
D693,035 S * 11/2013 Datz D26/28

FIG. 1 is a perspective view of a vehicle side view lamp showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures are included for illustrating unclaimed portions of the vehicle side view lamp and form no part of the claimed design.
